ROLLING BALL GAME DEVICE

Jesse J. Morsch, Douglas, Wyo.

Application October 16, 1952, Serial No. 315,080

6 Claims. (Cl. 273—110)

1

This invention relates to a game and amusement device and has for its principal object the provision of an amusement game which will require a certain amount of skill and which will produce unusual and intriguing motions and noises so as to be attractive to the players or users.

Another object is to provide an amusement device of the above character which will have a chance scoring feature which will enable it to 10 be used for various games of chance.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a top view of the improved game and amusement device;

Fig. 2 is a side view thereof;

Fig. 3 is a fragmentary top view, illustrating an alternate form of the device to be later described;

Fig. 4 is a vertical cross-section, taken on the line 4—4, Fig. 1;

Fig. 5 is a horizontal cross-section, taken on the line 5—5, Fig. 4;

Fig. 6 is a fragmentary, vertical section, taken on the line 6—6, Fig. 5;

Fig. 7 is an enlarged detail section, taken on the line 7—7, Fig. 4;

Fig. 8 is a side view of the portion shown in section in Fig. 7, illustrating a ball throwing arm employed in the device as it would appear in the locked position; and

Fig. 9 is a similar view, illustrating the ball throwing arm in the released position.

The improved game and amusement device employs a hollow, inverted, conical bowl 10 having a ball retaining rim 11 surrounding its upper open periphery. The bowl 10 is threaded or otherwise secured on an oscillatable post 12 to which it is locked by means of a suitable jam nut 13. The post 12 terminates at its bottom in a hinge member 14 by means of which it is hingedly mounted on a hinge shaft 15. The hinge shaft extends between, and is supported by, the sides of a rectangular housing 16 having an open bottom positioned over a base member 17 to which it is secured by means of suitable attachment screws 18.

It can be seen that the post 12 and the bowl 10 are free to tilt back and forth about the axis of the shaft 15. The post 12 is tilted by means of an eccentric member 19 which is connected to the post 12 by means of an attachment clip 20, 60

2

and which rides about an eccentric 21 mounted or formed on an eccentric shaft 22.

The shaft 22 is driven by means of a drive pinion 23 mounted thereon and meshing with a drive gear 24 which is fixedly mounted on a crank shaft 25 terminating in an actuating crank 26. The shafts 22 and 25 are also supported between the sides of the housing 16, with the crank 26 positioned on the exterior of the housing.

It can be seen that if the crank 26 be rotated, it will act through the mechanism above described to tilt the bowl 10 backward and forward. The tilting motion is more rapid than the crank rotation, due to the multiplying effect of the small pinion 23 and large gear 24.

A freely rolling ball is placed in the bowl 10. If the ball 27 is impelled about the bowl, it will hug the periphery of the bowl 10 within the retaining rim 11 through the action of centrifugal force. Now, if the crank 26 is simultaneously rotated, so that the lateral oscillations of the bowl 10 will coincide with the revolutions of the ball 27 about the periphery of the bowl, the speed of the ball 27 may be accelerated to any desired point.

When no further rotation is applied to the crank 26, the ball 27 will gradually decelerate until gravitational force exceeds centrifugal force, causing the ball 27 to fall to the bottom of the bowl 10.

As thus far described, the game makes a very attractive device requiring skill and muscle co-ordination on the part of the player to maintain the speed of oscillation at the proper point to provided the desired acceleration for the ball 27. The noise created by the rolling ball combined with the various oscillating and rotating movements makes an attractive amusement device.

For use as a game an annular series of holes 28 are formed about the periphery of the bottom of the bowl 10, and provided with suitable index or scoring numbers as illustrated, therefore, when the ball 27 comes to rest, it will be retained in one of the scoring holes and the number of that hole is added to the player's score.

If it is desired to still further increase the scoring probabilities, a plurality of pockets 29 may be positioned on the inclined side of the bowl 10 above the holes 28, as shown in the alternate form of Fig. 3, and these pockets may be given suitable index designations to play any desired game.

As thus far described, the initial impetus has been imparted to the ball 27 by hand. It is, however, rather difficult to attain the desired speed in this way. Therefore, means are provided for mechanically impelling the ball 27 about the bowl 10 during its initial rotation. This is accomplished by mounting a sleeve 30 around the post 12 within the bowl 10. A spool member 31 is rotatably and slidably mounted on the sleeve

30. A spiral spring 32 is engaged at one extremity to the bottom of the bowl 10 and at its other extremity to the bottom of the spool 31. The spring constantly tends to urge the spool both in a circumferential direction and an upward direction.

The maximum upward movement of the spool 31 is limited by a stop nut 33 locked on the post 12 by means of a lock nut 34. A stop pin 35 projects downwardly from the stop nut 33 to enter a pin hole 36 in the top of the spool. A throwing arm 37 is secured to the spool 31 in any desired manner, such as by means of an attachment ear and a bolt 38. The arm 37 extends radially outward, terminating in a forwardly opening ball pocket 39 positioned to rotate within the radius of the retaining rim 11.

It can be seen that if the spool 31 is pressed downwardly until the pin hole 36 releases the pin 35, the spool may be rotated rearwardly to wind the spring 32. The spool is retained in its lowermost position by the pin 35 riding on the top thereof, as shown in Fig. 8. Now, if the ball 27 be placed in the pocket 39 and the arm 37 released, the spring will cause the arm to whirl the ball 27 about the bowl 10 until the pin hole 36 reaches a position below the pin 35. The spring 35 will now stop further rotation of the spool and will snap the latter upwardly to the position of Fig. 7 to allow the ball to continue under its own inertia and to elevate the pocket 39 from the path of the ball 27, so that the latter can continue to rotate without interference. This provides an easily used mechanical actuator for the ball 27.

If it is desired to hold the arm 37 in its wound-up or set position, this may be accomplished by means of a tiltable latch 40 hinged intermediate its extremities as shown at 41 on the side of the bowl 10 and having an inner hooked extremity which can be swung to extend downwardly within the bowl 10 into the path of the pocket 39. The hooked inner extremity is lifted out of the path of the pocket 39, by pressing on the outer extremity of the latch 40, to allow the spring 32 to swing the arm 37. This provides a highly efficient means or trigger for releasing the arm 37.

Means are provided which may be used for releasing the latch 40 if desired. This is accomplished by hinging an L-shaped lifting lever 42 within the retaining rim 11. The lower extremity of the L-shaped lever swings upwardly when the upper extremity is swung sidewardly. The upwardly swinging extremity lifts the latch 40 to release the arm 37, as shown in Fig. 2.

Means are also provided for swinging of the lifting lever 42 by chance. This is accomplished by mounting a rotatable bracket member 43 on an anti-friction bearing 44 held on the upper extremity of the post 12 by means of a retaining screw 45. A cap member 46 is concentrically mounted in the bracket member 43 and projects upwardly therefrom. The bracket member 43 and its cap 46 are free to rotate about the axis of the post 12. A governor arm 47 carrying a governor weight 48 is hinged on a hinge pin 49 in the bracket member 43 so that it may swing in a vertical plane. The governor arm is resiliently supported by means of a tension spring 50.

Let us assume that the ball 27 has been placed in the pocket 39; that the spool 31 has been depressed to release the locking pin 35; that the arm 37 has been rotated rearwardly to wind the spring 32 and engaged behind the latch member 40; and that the lifting lever 42 is in a substan-

5 tially vertical position out of contact with the latch 40. The operator now twirls the cap 46 and the attached governor arm 47 in a clockwise direction, and simultaneously rotates the crank
